UNITED STATES PATENT OFFICE.

WILLIAM M. GUYSE AND HARRY H. GUYSE, OF BILLINGS, MONTANA.

METAL BUILDING LATH.

Application filed September 18, 1921. Serial No. 500,294.

To all whom it may concern:

Be it known that we, WILLIAM M. GUYSE and HARRY H. GUYSE, citizens of the United States, residing at Billings, in the county of 5 Yellowstone and State of Montana, have invented certain new and useful Improvements in Metal Building Laths, of which the following is a specification.

The present invention relates to metal 10 building laths and has primarily for an object the production of a lath simple in construction and easy of application.

A co-ordinate object of the invention is to provide an inexpensive metal lath with 15 which the plastic material may be quickly and conveniently engaged and in view of the peculiar formation of the lath will be locked from displacement or disintegration.

The above and other objects of this invention will be in part described and in part understood from the present preferred embodiment of the invention taken in connection with the accompanying drawings wherein:—

25 Fig. 1 is a fragmentary front elevational view of laths constructed in accordance with this invention;

Fig. 2 is a similar view showing the plastic material and woodwork applied to the lath;

30 Fig. 3 is a vertical sectional view of the same;

Fig. 4 is a detail fragmentary rear elevational view illustrating the manner in which the plastic material projects therethrough; 35 and

Fig. 5 is a fragmentary vertical sectional view of one of the laths per se showing to advantage one of the punched out openings of the lath.

40 A single lath constructed in accordance with the present invention consists of a metal sheet 6 which in the present instance is shown to be of an oblong configuration and is relatively thin. It is of course to be

45 understood that the lath may be made in any desired size, of any preferred configuration and of any suitable gauge metal in order that the best results might be obtained for the particular work undertaken.

50 It has been found from experiment, however, that a lath constructed substantially in ac-

cordance with this invention will produce satisfactory results.

Each lath has a plurality of oblong staggered openings 7 punched therethrough in 55 a manner which will provide a smooth front face against which the plastic material is engaged. Inclined flanges 8 project rearwardly from each of the openings 7 as illustrated to advantage in Fig. 3 of the drawings. Furthermore as shown in Figs. 3 and 5 of the drawings the openings 7 are of a substantially truncated cone shape in cross section to provide relatively large openings in the front for the plastic material to engage, whereas the rear end of each opening is constricted to limit the volume of plastic material passed therethrough. Consequently, the plastic material, indicated in the drawings at 9 presents a smooth finished 70 face on the front of the lath and permits an overflow of the plastic material through the flanges or lips 8 on the back of the lath serving to unite or bond the plastic material to the lath. It is of course apparent 75 that when the plastic material hardens it will be as a unit with the lath 6 thereby reducing possibility of breakage or disintegration to a minimum.

The use of a lath constructed in accordance with this invention will enable a plasterer to scratch-coat five hundred yards of lath per day whereas it is recognized in use of laths at the present time that it is difficult for a plasterer to scratch-coat more 85 than three hundred yards per day. Also the amount of plastic material used to cover this surface is materially reduced since it is possible to use a thinner coat of the plastic material in view of the peculiar manner 90 of bonding the latter to the lath. Also the lath can be made relatively larger than standard laths to reduce the amount of frame work used to which the lath is secured.

Various changes may be made in this device especially in the details of construction, proportion and arrangement of parts without departing from the spirit and scope of the invention as covered by the appended claim.

100 What is claimed is:—

A metal lath for plastic walls including

an integral metal body provided with openings punched through from the plastic receiving side of the body to provide a lip on each side of each opening through which the 5 plastic material is forced from the plastic receiving side of the lath substantially as described.

In testimony whereof we affix our signatures in presence of two witnesses.

WILLIAM M. GUYSE.
HARRY H. GUYSE.
